UNITED STATES PATENT OFFICE.

ALBERT W. BLACK, OF ST. LOUIS, MISSOURI.

COLD-STORAGE HOUSE.

SPECIFICATION forming part of Letters Patent No. 433,316, dated July 29, 1890.

Application filed March 6, 1890. Serial No. 342,829. (No model.)

To all whom it may concern:

Be it known that I, ALBERT W. BLACK, of the city of St. Louis, in the State of Missouri, have invented a certain new and useful Improvement in Cold-Storage Houses, of which the following is a full, clear, and exact description, reference being had to the accompanying drawings, forming part of this specification.

My invention relates to certain improvements in the arrangement and construction of cold-storage houses or permanent refrigerators; and my invention consists in features of novelty hereinafter fully described, and pointed out in the claims.

Figure I is a vertical section illustrative of my invention. Fig. II is a horizontal section taken on line II II, Fig. I.

In making my present invention I have had in mind or view the idea of making such a structure in which the foul odors and dampness from the cellar and sides of the box, as well as the heated air in the walls, which may be due to outside influences, are removed or carried off and not permitted to enter the storage-chamber; also, the idea of making such a structure in which the supporting-beams to the ice-floor may be put in position after all the other work on the walls, &c., has been finished; also, the idea of producing an iron floor in the ice-chamber, which is constructed to drain the melted ice to a delivery-trough, and by means of which the ice-box is made water-tight at bottom at a very small cost; also, the idea of producing a ceiling or roof to the ice-box so inclined as to produce a circulation of air around and from the ice-box to, through, and from the storage-room, and, also, the idea of producing circular-formed corners to the upper portion of the ceiling, which facilitates the circulation, without the condensation of dampness at such points; and with these objects in view I have produced the construction which I will now describe, having reference to the drawings.

1 represents the outer walls of the structure, having a roof or canopy 2. These walls and this canopy are constructed with passages or flues 3, through which the damp and foul air from the cellar of the structure pass and escape through openings 4 at the upper portion

of the structure, as shown in Fig. I. These flues and passages also carry off the heated air of the walls which may be formed, or due to outside influence or temperature of the atmosphere, and thus afford a protection in the way of excluding warmth from the ice-box and storage-room. After the walls and canopy of the structure are formed I place within the lower portion of the walls a framing 5, consisting of suitable vertical and horizontal strips or beams, and upon this framing the supporting-beams 6 of the ice-chamber are placed after the work on the outer walls and canopy has been completed. By thus constructing the support for the ice-box it is not in the way and does not interfere with the work on the walls and the canopy, as the beams are not put in place until after such work has been completed.

70 7 represents the ice-box, which rests on the beams 6. The floor of this box is lined with galvanized-iron strips 8, placed diagonally across the floor of the box, with the lower edge of each strip lapped over the adjacent edge of the strip beneath, as shown in Fig. I, and also by dotted lines in Fig. II. At the lower side of the inclined floor of the ice-box is located a trough 9, which carries the melted ice to a suitable delivery-spout, and through which it is transferred away from the box, the lower side of one wall of the ice-box being provided with a suitable number of leak ports or ducts 9^a, leading from the lower end of the ice-box into the trough. By thus constructing a floor 80 it will be seen that the water will pass from one strip onto another and there will be no tendency for it to leak through between the overlapping edges of the strips, as there is a downward incline from each of the joints. A 85 lining thus formed is exceedingly cheap in structure and can be quickly applied.

90 The roof or top 10 of the ice-box is made inclined, as shown in Fig. I, and at the top of the lower side of the ice-box there is an opening 11, through which the cold air may pass from the ice-box to the storage-room 12. 13 represents a flue or chamber at the back, top, and front of the ice-chamber. The air circulates from the storage-room up behind the 100 ice-box, thence over the ice-box, and thence down in front of the ice-box into the storage-

room again. The beams 6, of course, are placed a short distance apart and the air circulates between them. As the air circulates around the ice-box, it is chilled or cooled, and owing to the inclination of the top of the box a natural draft is created to produce the circulation, as shown by the arrows. While this air, which is necessarily warmer than the air within the ice-box, will not enter the ice-box, yet the surplus of air in the ice-box will escape through the opening 11 and pass into the storage-room. The ceiling of the housing is provided with rounded corners 14, which assist in the perfect circulation of air from the storage-room around the ice-box and prevents the collection of dampness and condensation of moisture at these points.

With a structure of this kind I produce a cold-storage house wherein there is a perfect circulation without ventilation and without the introduction of outside air, the result being a very great saving of ice and a more perfect refrigeration of the contents of the storage-room, and sweat in the ice box or chamber is also avoided, because no warm air comes in contact with the ceiling of the ice-chamber. It will be seen that all the roofs or tops are substantially parallel and inclined in but one direction, so that there will be no counter-currents around the ice-box.

I claim as my invention—

1. In a cold-storage house, the combination of the outer walls and canopy provided with air-passages and an inner ice-box and storage-room closed from communication with the outside atmosphere, said ice-box and storage-chamber having parallel inclined tops with a space between them, substantially as set forth.
2. In a cold-storage house, an ice-box having an inclined floor provided with a lining composed of overlapping diagonally-arranged strips and a trough at the lower side of said floor, substantially as and for the purpose set forth.
3. In a cold-storage house, the combination of the outer walls and canopy, an ice-box and

storage-room located within the outer walls and canopy, said ice-box having an imperforate roof or top inclined in but one direction 50 and forming an inclined air-passage between the top of the ice-box and the canopy of the housing, and the latter canopy being also inclined in but one direction, substantially as and for the purpose set forth. 55

4. In a cold-storage house, the combination of the outer walls and canopy forming a housing and an ice-box and storage-room located within the housing, the ceiling of said housing having rounded corners 14, and both the 60 ceiling of the housing and the top of the ice-box being imperforate and inclined in but one and the same direction, substantially as and for the purpose set forth.

5. In a cold-storage house, the combination 65 of the outer walls having air-inlets at bottom and top, respectively, an inclined canopy or roof arranged on said walls, the inner walls arranged at a distance from the outer walls and provided with a closed bottom or floor 70 and a closed top or roof inclined in but one direction, forming an inner room or chamber having no communication whatever with the space between the inner and outer walls or with the external atmosphere, the independent framing 5, arranged wholly within the said inner chamber, the cross-beams 6, resting upon and supported solely by said framing, and an ice-box supported on said framing in the upper part of the inner chamber and having its top inclined in a single direction and the side opening 11 at the upper side of its lower end, the inner upper corners of said ice-box and inner chamber being rounded and said ice-box being completely closed 85 against communication with the said inner chamber save through the said side opening 11, substantially as and for the purposes set forth.

ALBERT W. BLACK.
